United States Patent Office.

R. B. PARKS AND J. R. PARKS, OF NEPONSET, ILLINOIS.

Letters Patent No. 61,091, dated January 8, 1867.

IMPROVEMENT IN CULTIVATOR.

The Schedule referred to in these Letters Patent and making part of the same.

TO ALL WHOM IT MAY CONCERN:

Be it known that we, R. B. PARKS and J. R. PARKS, of Neponset, Bureau county, State of Illinois, have invented a new and improved Cultivator; and we do hereby declare that the following is a full, clear, and exact description thereof, which will enable others skilled in the art to make and use the same, reference being had to the accompanying drawing forming part of this specification, in which—

Figure 1 is a plan or top view of our invention.

Figure 2, a side sectional view of the same, taken in the line $x-x$, fig. 1.

Similar letters of reference indicate like parts.

This invention relates to a new and improved cultivator of that class designed for cultivating crops which are grown in hills or drills, and it consists in a novel construction and arrangement of parts, as hereinafter fully shown and described, whereby the driver will have full control over the ploughs, so that the latter may be moved or adjusted in a lateral direction to conform to the sinuosities of the rows, and also raised and lowered to regulate the depth of their penetration into the earth.

A represents a rectangular frame, which is mounted on two wheels, B B, having the driver's seat, C, on its rear part. D D represent two plough beams, which are attached to the under sides of the frame A by joints a, said beams having a longitudinal position relatively with the frame A, parallel with each other, and allowed to turn or swing freely from their points of suspension, to wit, the joints a. Each plough beam D has two standards E E' attached to it by pivots b, the standards E being attached to the inner side of the beams, and the standards E' attached to the outer sides of the same, the standards E being in advance of the standards E'. These standards are connected by cords or chains c to levers F, secured to the beams D, said cords or chains passing over pulleys d at the sides of the beams. The levers F are retained or held in place at any point within the scope of their movement by catching into toothed semicircular racks G attached to the beams. Each beam D has a knee or right-angular bar, H, attached to it, the upper ends of which are pivoted to the ends of a bar, I, and the lower ends connected by links e to treads J J, the front ends of which are connected to the front end of frame A, and the rear ends being within reach of the feet of the driver on seat C. K represents ploughs, which are secured to the lower end of the standards E E', as follows: The standards have each a metal bar, L, secured to them by a pivot, f, and through the upper end of each bar L a set-screw, g, passes. These set-screws bear against the standards E E', as shown clearly in fig. 2. The ploughs K are attached to the bars L, and it will be seen by referring to fig. 2 that by adjusting the set-screws g the ploughs K may be placed in a more or less angular or oblique position, as occasion may require. It will also be seen that the ploughs may be adjusted higher or lower to regulate the depth of the furrow, as may be required, by actuating the levers F, and by this means may be raised entirely out of the ground when necessary. By actuating the treads J J the plough beams D D may be turned and the ploughs K moved laterally to conform to the sinuosities of the rows of plants. Thus it will be seen that the driver has full control over the ploughs, and the crop may be perfectly cultivated, however uneven the ground or crooked or sinuous the rows of plants may be.

Having thus described our invention, we claim as new, and desire to secure by Letters Patent—

1. The angular bars H, pivoted to bar I, and connected with the treads J by links e, in combination with the beams D, and operating substantially as described for the purpose specified.
2. The pivoted bars L in combination with the ploughs K and standards E E', and set-screw g, substantially as described for the purpose specified.

R. B. PARKS,
J. R. PARKS.
